US00D614293S

(12) United States Design Patent
Nelson et al.

(10) Patent No.: US D614,293 S
(45) Date of Patent:  *Apr. 20, 2010

(54) SANITARY TOWEL

(75) Inventors: Naomi Ruth Nelson, Cincinnati, OH (US); Christopher Duane Heckman, Cincinnati, OH (US)

(73) Assignee: The Procter & Gamble Company, Cincinnati, OH (US)

() Term: 14 Years

(21) Appl. No.: 29/326,719

(22) Filed: Oct. 23, 2008

(30) Foreign Application Priority Data

May 7, 2008 (EM) 000930433-0008

(51) LOC (9) Cl. 24-04

(52) U.S. Cl. D24/124; D24/125

(58) Field of Classification Search D24/124-125; 604/385.07, 358, 363, 364, 368-375, 385.01, 604/385.03, 385.14, 385.23, 387, 390; D5/37-43, D5/53, 56, 57, 58, 60-62

See application file for complete search history.
